OSCAR C. KREIS, OF DETROIT, MICHIGAN, ASSIGNOR TO CONTINENTAL MOTORS CORPORATION, OF DETROIT, MICHIGAN, A CORPORATION OF VIRGINIA

MANIFOLD

Original application filed November 3, 1927, Serial No. 230,730. Divided and this application filed March 30, 1929. Serial No. 351,278.

This invention relates to internal combustion engines and refers more particularly to an intake manifold.

In the present types of intake manifolds, particularly for engines of six and more cylinders, difficulty has been experienced in distributing the combustible mixture equally to all the cylinders. Where the usual types of branched intake manifolds are used the 10 unvaporized particles of the gaseous mixture frequently are carried into certain cylinders to a greater extent than into other cylinders resulting in general inefficient engine performance. In order to reduce this condition as much as possible the intake manifold is ordinarily jacketed to apply heat to the intake mixture, a portion at least of the wet particles being thereby vaporized. However such heating of the mixture is generally 20 admitted to reduce the volumetric efficiency of the engine.

In my invention I provide a separate manifold conduit for each cylinder so that any wet or unvaporized particles of fuel or mixture entering any of the several conduits will eventually reach its communicating cylinder avoiding the possibility of supplying any one cylinder with more of the unvaporized particles than any other. A substantially 30 equal distribution of intake mixture is thereby afforded for each cylinder resulting in increased engine efficiency. At the same time I contemplate the elimination of much, if not all, of the manifold heating which is ordinarily employed with resulting increased engine efficiency and a better engine power output.

A further beneficial result of my invention resides in providing independent manifold conduits for the cylinders whereby the gas surge to any cylinder will not be materially interfered with by any other cylinder intake.

In carrying out my invention I find it desirable to provide a chamber communicating with the mixing carburetor, the individual conduits for each cylinder being branched generally longitudinally of the engine to the respective cylinders. With such an arrangement the conduits may be made of relatively large cross sectional area, affording

greater power output for the engine. My invention is especially useful in engines having six cylinders in line, greater difficulty of the aforesaid nature having been experienced with such an engine than in the four cylinder type for example.

This application is a division of my co-pending application Ser. No. 230,730 filed November 3, 1927.

Other features of my invention reside in the combination and arrangement of parts more particularly hereinafter described and claimed.

Referring to the drawings in which like reference characters indicate corresponding parts,

Fig. 1 is a side elevation view of an internal combustion engine showing my manifold applied thereto,

Fig. 2 is a sectional elevation view of the intake manifold, and

Fig. 3 is a detail sectional view through 3—3 of Fig. 1.

In the drawings reference character A represents the engine, illustrated as having six cylinders in line, B representing the exhaust manifold and C the intake manifold. The engine A may be of the well known general construction such as used for automotive vehicles.

The intake manifold C comprises a central chamber 10^a which may be divided by a partition 29, the chamber extending generally vertically from an inlet 11 which communicates with the mixing carburetor preferably of the well known duplex or dual type affording independent mixture supply to the two groups of conduits which communicate with the respective divided portions of chamber 10^a where partition 29 is employed. The chamber 10^a is provided with front wall 12, rear wall 13, and side walls 14 and 15. The chamber 10^a is preferably substantially rectangular in cross-section and may have its side walls 14, 15 tapering upwardly and inwardly to facilitate the fuel distribution. Thus the chamber volume is proportioned to the demand of the conduits referred to hereinafter.

Extending longitudinally of the engine 100

from the chamber 10^a are conduits 16^a, 17^a, 18^a, 19^a, 20^a, 21^a, respectively provided with outlets 22, 23, 24, 25, 26, 27, which communicate with the respective cylinder intakes of the engine.

The conduits 16^a, 17^a communicating with the central cylinders preferably communicate with the chamber 10^a opposite each other in the walls 15, 16 respectively, the conduits 18^a, 19^a leading to the second and fifth cylinders

10 ^{10^a} leading to the second and third cylinders having their communication with the chamber ^{10^a} likewise in opposite relationship next above the conduits ^{16^a}, ^{17^a}, and the conduits ^{20^a}, ^{21^a} leading to the end cylinders having similarly aligned openings in the chamber ^{10^a}.

The entire manifold C may be cast integrally with single dividing walls between adjacent conduits as shown. The areas of the conduits are preferably relatively greater than standard practice, any precipitation of wet particles resulting from such increased area being carried along to the particular cylinder communicating with the respective con-

25 duits. By arranging the conduits and chamber 10^a as shown, the distance from the chamber inlet 11 to each cylinder is equalized to some extent. Thus conduits 16^a, 17^a supplying the central cylinders open into chamber 30 10^a near the bottom thereof, the chamber openings of conduits 18^a, 19^a supplying the intermediate cylinders being next above, and the chamber openings for conduits 20^a, 21^a supplying the end cylinders being next above 35 or near the top of chamber 10^a.

35 I have not illustrated the usual heating jacket around the intake manifold above the carburetor connection inasmuch as such jacketing is well known in the art and may be employed as desired. However, one feature 40 of my invention resides in a construction which will eliminate much, if not all, of the heating ordinarily employed as previously set forth. I do not limit my invention, apart 45 from the claims, to the presence or absence of a heating jacket since in either event my manifold construction will afford improved results.

What I claim as my invention is:

50 1. An intake manifold for multi-cylinder internal combustion engines comprising fuel mixture chamber means opening vertically for admission of a fuel mixture, and a plurality of conduits each opening into the said 55 chamber means and each extending for connection to an individual engine cylinder intake, the conduit openings to the chamber means being arranged substantially in a common vertical plane with those conduits supplying the inner cylinders located below 60 those conduits supplying the outer cylinders.

2. An intake manifold for a six cylinder internal combustion engine comprising chamber means opening downwardly for admission of a fuel mixture and closed at the

top, and six conduits arranged in two groups of three vertically spaced conduits, each conduit opening into the chamber and extending generally longitudinally of the engine for connection with a single cylinder intake, 70 the conduit openings for the central pair of cylinders being below the conduit openings for the second and fifth cylinders and the latter conduit openings being below the conduit openings for the end cylinders. 75

3. An intake manifold for multi-cylinder internal combustion engines comprising a vertical chamber opening downwardly for admission of a fuel mixture, and a plurality of conduits vertically arranged in groups, the conduits of each group opening into the said chamber and each conduit of each group opening into the said chamber and each conduit of each group extending for communication with a single cylinder intake, the cylinders nearest the chamber having their said conduit openings below those which supply cylinders relatively remote from the chamber. 80 85

4. An intake manifold for a six cylinder internal combustion engine comprising a tapering vertically extending chamber opening downwardly for admission of a fuel mixture and closed at the top, and six separate conduits arranged in two groups of three conduits, each conduit opening into said chamber and each connected with a single cylinder, the conduit openings to the chamber means being arranged substantially in a common vertical plane with those conduits supplying the inner cylinders located below those conduits supplying the outer cylinders. 100 95 100

5. An intake manifold for multi-cylinder internal combustion engines comprising a vertical chamber opening downwardly for admission of a fuel mixture, and a plurality of conduits arranged in groups, the conduits of each group opening into the said chamber and each conduit of each group extending for communication with a single cylinder intake, the chamber conduit openings of each group being spaced vertically of the chamber with these conduit openings supplying the end cylinders spaced above those conduit openings supplying inner cylinders. 115

6. An intake manifold for a six cylinder internal combustion engine comprising a vertically extending chamber opening downwardly for admission of a fuel mixture and closed at the top, and six separate conduits 120 arranged in two groups of three conduits, each conduit opening into said chamber and each connected with a single cylinder intake, the chamber conduit openings of each group 125 being spaced vertically of the chamber with those conduit openings supplying the end cylinders spaced above those conduit openings supplying the inner and intermediate cylinders.

7. An intake manifold for internal com- 130

bustion engines comprising a vertical chamber opening downwardly for admission of a fuel mixture and a plurality of conduits arranged in groups, the conduits of each group opening into the said chamber and each conduit of each group extending for communication with a single cylinder intake, the chamber conduit openings of each group being spaced vertically of the chamber, the conduits connecting the central pair of cylinder intakes communicating with the lower portion of said chamber.

8. An intake manifold for internal combustion engines comprising a vertical chamber opening downwardly for admission of a fuel mixture and a plurality of conduits arranged in groups, the conduits of each group opening into the said chamber and each conduit of each group extending for communication with a single cylinder intake, the chamber conduit openings of each group being spaced vertically of the chamber, the conduits connecting the central pair of cylinder intakes communicating with the lower portion of said chamber, the conduits connecting the end cylinder intakes communicating with the upper portion of said chamber.

9. An intake manifold for internal combustion engines comprising a chamber having opposed front and rear walls, opposed side walls, a top wall, and opening downwardly for admission of a fuel mixture, a group of conduits opening into one of the chamber side walls and a second group of conduits opening into the other of the chamber side walls, each conduit of each group extending for connection with a single cylinder intake, the conduit openings to the chamber means being arranged substantially in a common vertical plane, said chamber having a central vertical portion depending from the top wall and extending substantially to the chamber opening.

10. An intake manifold for internal combustion engines comprising a chamber opening downwardly for admission of a fuel mixture, and a plurality of conduits each opening into the said chamber and each extending for connection to an individual engine cylinder intake, the conduit openings to the chamber means being arranged substantially in a common vertical plane with those conduits supplying the inner cylinders located below those conduits supplying the outer cylinders, said chamber having a partition dividing the chamber into two non-communicating portions, each chamber portion supplying a group of the said conduits with fuel mixture.

11. An intake manifold for a six cylinder internal combustion engine comprising a chamber opening downwardly for admission of a fuel mixture and closed at the top, and six conduits arranged in two groups of three conduits, each conduit opening into the

chamber and extending generally longitudinally of the engine for connection with a single cylinder intake, the cylinders nearest the chamber having their said conduit openings below those which supply cylinders relatively remote from the chamber, said chamber having a partition dividing the chamber into two non-communicating portions each chamber portion respectively supplying the said groups of conduits with fuel mixture.

12. An intake manifold for an in line internal combustion engine comprising a chamber opening downwardly for admission of a fuel mixture, and a plurality of conduits each opening into the said chamber and each extending for connection to an individual engine cylinder intake, said chamber located substantially midway of the ends of the engine and having a partition extending in a plane substantially perpendicular to the longitudinal axial plane of the engine for dividing the chamber into two non-communicating portions, one chamber portion supplying a group of conduits connecting the cylinders in front of said chamber and the other chamber portion supply a group of conduits connecting those cylinders located to the rear of said chamber.

In witness whereof, I hereunto subscribe my name this 26th day of March, 1929.
